UNITED STATES PATENT OFFICE.

PAUL M. ROSENWASSER, OF CLEVELAND, OHIO, ASSIGNOR TO THE MAURICE COMPANY, OF CLEVELAND, OHIO, A CORPORATION OF OHIO.

MEASURING ATTACHMENT FOR CANS.

1,346,558.

Specification of Letters Patent. Patented July 13, 1920.

Application filed July 25, 1919. Serial No. 313,178.

To all whom it may concern:

Be it known that I, PAUL M. ROSENWASSER, residing at Cleveland, in the county of Cuyahoga and State of Ohio, have invented 5 a certain new and useful Improvement in Measuring Attachments for Cans, of which the following is a full, clear, and exact description, reference being had to the accompanying drawings.

10 The object of this invention is to provide in a very simple and cheap form a measuring device for a friction top can. In carrying out my invention I secure to the friction top or cap a downwardly projecting tubular member, which, with the cap constitutes a cup when the cap is removed. By this arrangement there is always at hand an appropriate measure for the contents of the can. For many substances such measuring 15 container is extremely useful. Mention may be made for instance of household food materials, as chocolate or coffee, which are ordinarily used in comparatively definite amounts.

20 In making the device in the simplest form, I provide a can with an opening surrounded by a down-turned internal flange, and I provide a laterally flanged cap with a depressed central portion which could pass 25 loosely into the can opening, and I surround such central portion by a tubular member which is secured to the cap, and has the upper portion of its exterior adapted to make a tight fit with the flange of the can. Preferably this tubular member is outwardly 30 flanged at its upper edge and is embraced by a lapped-over edge of the flange of the cap. Such a measuring cap may depend freely into the can and act as a friction top 35 in the usual manner, but whenever removed provides a measuring device well adapted 40 for dispensing the contents of the can.

45 My invention is illustrated in the drawings hereof, and is hereinafter more fully described, and the essential characteristics are summarized in the claims.

50 In the drawings, Figure 1 is a perspective view of a can equipped with my measuring friction top. Fig. 2 is a cross section through the can and cap member, the thickness of the material being exaggerated in this view for clearness of illustration.

55 In the drawings, A represents any suitable can having a top *a* which has an orifice

with a down-turned flange *a*¹, this orifice 55 being preferably round. B represents the cap proper, and C the tubular extension to provide the measuring effect. The top has a depressed central portion *b* with a substantial vertical wall *b*¹, and an outwardly 60 extending top flange *b*². The tube C snugly embraces the exterior of the wall *b*¹ and has at its upper edge an upward flange *c* which is embraced by the curled-over edge of the top flange *b*² of the cap. If desired, any 65 annular space between the measuring extension C and the cap wall *b*¹ may be filled with solder.

The tubular wall C preferably extends 70 inward slightly after it leaves the cap to enable it to be passed freely into the flanged opening in the can. When in place its upper portion has a tight fit with such flanged opening, providing the desired friction top.

75 It will be seen that my measuring top is very simple and cheap to construct. The extension is ordinarily out of the way and enables the can to be used as an ordinary friction top can, the cover being removed and replaced as usual. At the same time 80 there is always at hand a measuring device appropriate to the contents of the can.

I claim:

1. The combination of a can having an orifice, a cap having a depressed portion 85 adapted to enter the orifice, and having an outward flange at its upper edge, and a tubular extension having an open end remote from said cap and having a flange at its upper edge rigidly secured to said cap, said 90 cap and extension comprising a measuring device.

2. The combination of a can having an opening, a cap having a depressed central portion, a vertical wall and an outward 95 flange, a tubular extension surmounting said vertical wall, and having an outward flange at its upper end, the flange of the cap being curled over and beneath the flange of the extension, the extension below the 100 cap being adapted to loosely pass through the flange of the can and the portion of the extension surrounding the wall of the cap being adapted to make a frictional snug engagement with the flange of the can. 105

In testimony whereof, I hereunto affix my signature.

PAUL M. ROSENWASSER.
